SOCK OR SIMILAR ARTICLE

Lionel Lasar, Lynbrook, N. Y.

Application June 5, 1953, Serial No. 25,336

Term of patent 3½ years

(Cl. D47—7)

To all whom it may concern:

Be it known that I, Lionel Lasar, a citizen of the United States of America, residing at Lynbrook, in the county of Nassau and State of New York, have invented a new, original, and ornamental Design for a Sock or Similar Article, of which the following is a specification, reference being made to the accompanying drawing, forming a part thereof.

The figure is a side view of a sock, embodying my new design; and the opposite side is like the side shown.

I claim:

The ornamental design for a sock or similar article, substantially as shown and described.

LIONEL LASAR.
